Amory, Garrison of, Littleton, Massachusetts

Letters Patent

The Schedule referred to in these Letters Patent and making part of the same containing a description in the words of the said Amory Garrison in himself of his improvement in the machine for washing clothes.

I, Do. of known that I, Amory Garrison of Littleton, in the County of Middlesex and State of Massachusetts, have invented a new and useful improvement in the machine for washing clothes which is described as follows:— This machine consists of a wooden frame whose bottom is covered by an segment of a circle of a radius a little greater than the radius of the circle in which the beating move. The ends are rounded inwardly and at one end there is an inclined flat made board. The which is suspended on a hinge. On the bottom of the Box is a hole and plug for drawing off the water. At the sides of the Box are two standards to the ends of which are suspended two bushes by pins and the bushes consist of blocks of pine wood covered on the bottom and cut into steps or T's. The way by which they are suspended is made flat with other bushes and in them to permit them to play over the shaft passing through the standards to which the power is applied in moving an ironed into this shaft connected to the beating by connecting rods. Attached to the ends of arms fastened to and projecting from the bushes.

is the end of the shaft an iron or iron by which the machine is operated. The shaft and iron a strong plait into the Box with the clothes to be washed the shaft is attached to the right and left by the bushes. This motion causes the bushes to move in a vibrating motion by which means the clothes are thrown to the ends of the Box and by the peculiar shape of the bushes and a corresponding shape in the beating. The clothes are kept constantly moving over and receives new stroke from the beating in a fresh place till they are completely cleaned. But should any of the pieces of apparatus become cleaned it can be drawn on the flat board by hand.

"That I claim as my invention and which I desire to secure
